[57] CLAIM

The ornamental design for car seat toy holder, as shown and designed.

DESCRIPTION

FIG. 1 is a perspective view of a car seat toy holder showing my new design;

FIG. 2 is a top plan view thereof;

FIG. 3 is a right side elevational view thereof;

FIG. 4 is a bottom plan view thereof;

FIG. 5 is a left side elevational view thereof;

FIG. 6 is a rear elevational view thereof; and,

FIG. 7 is a front elevational view thereof.

The broken line showing of the car seat is for illustrative purposes only and forms no part of the claimed design.

FIG. 4

FIG. 5

FIG. 7

FIG. 6
